UNITED STATES PATENT OFFICE.

JOHN McMYLER, OF CLEVELAND, OHIO, ASSIGNOR TO THE McMYLER MANUFACTURING COMPANY, OF CLEVELAND, OHIO, A CORPORATION OF OHIO.

HOISTING AND CONVEYING APPARATUS.

No. 891,631.

Specification of Letters Patent.

Patented June 23, 1908.

Application filed October 6, 1906. Serial No. 337,696.

To all whom it may concern:

Be it known that I, JOHN McMYLER, a citizen of the United States, residing at Cleveland, in the county of Cuyahoga and State of Ohio, have invented a certain new and useful Improvement in Hoisting and Conveying Apparatus, of which the following is a full, clear, and exact description.

There is a type of hoisting and conveying apparatus which includes a bridge, a trolley movable thereon and provided with sheaves from which the bucket holding and closing ropes depend and a clam shell bucket suspended from those ropes. In apparatus of this type, the hoisting and holding ropes, as well as the ropes by which the trolley is moved along the bridge, or some of said ropes, extend in both directions from the trolley to the ends of the bridge. The bridges of this type of apparatus are sometimes quite long. As a result these ropes sag between their supported points, and thereby, for reasons well understood in this art, the satisfactory operation of the apparatus is sensibly impaired. Various forms of sag carriers have been proposed for the purpose of supporting these ropes at points intermediate to the trolley and bridge ends, but such devices, in the forms in which they have heretofore been constructed, have not proved entirely satisfactory; for which reason, apparently, none of them have gone into extensive use.

The present invention is an improved sag carrier intended particularly for use in an apparatus belonging to the class which has been hereinbefore broadly described.

The sag carrier constituting the present invention consists of two small trolleys located at opposite ends of the main trolley, and movable upon the bridge, and carrying sheaves which support the ropes, which would otherwise sag, and connections between the main trolley and the sag carrier trolleys by which the latter are moved in the same direction as the main trolley but at substantially half the speed.

The invention also resides in the means substantially as shown whereby said sag carrier trolleys are moved at the required speed whenever the main trolley is moved.

The invention is shown in the drawing in the best form now known to me, and is hereinafter described and definitely pointed out in the claims.

In the drawing Figure 1 is a side elevation, showing the invention when the main trolley is in its central position. Fig. 2 is a similar view showing the invention when the main trolley has been moved about half way from its central position toward one end of the bridge. Fig. 3 is an end view of one of the sag carrier trolleys.

In the drawing A and A' represent the tracks which are usually fixed upon a bridge.

B represents the main trolley, which lies for the most part between said tracks and is provided with wheels b, which ride upon the tracks.

C represents a clam shell bucket, which may be of any suitable construction. D represents the closing ropes, and E the holding ropes for said bucket. These ropes pass to and over sheaves b' b'' mounted on trolley B, as shown in dotted lines in the drawing; and then extend in opposite directions toward the ends of the bridge.

F represent the trolleying ropes which are secured to the trolley and extend in opposite directions therefrom toward the ends of the bridge. It has not been thought necessary to show the bridge, or the sheaves thereon by which these ropes are supported and guided, nor the means whereby these various ropes are taken in and paid out for the purpose of lowering and opening the bucket, or closing and raising it, or for causing the trolley to move in either direction upon the bridge. A great variety of constructions suitable for these purposes are well known in this art, and any mechanism suitable for the purpose may be employed.

G—G represent the two sag carrier trolleys, which are respectively located on opposite sides of the main trolley B and are provided with wheels g which ride upon the tracks A. Each of these sag carrier trolleys includes two or more parallel vertical plates g', which support the rod g'' on which are mounted as many sheaves g''' as are required to support the various ropes. A rope K is attached at its end to the remote ends of the two trolleys G. This rope, from its points of attachment with the two trolleys, extends in opposite directions to the ends of the bridge and then over suitable sheaves as M—M N—N. Two other ropes J J' are provided, each of which is dead ended at one end as at j and j', and extends from this fixed end past the center of the

bridge, then over a sheave g^4 on one of the trolleys G and thence back to the main trolley B to which it is fixedly connected.

It is evident that as the main trolley B is moved, toward one end or the other of the bridge, it drags along with it that one of the trolleys g which is then on behind it but because of the manner of the reeving of ropes J and J', the movement of said trolley G will only be half as fast as the movement of the trolley B. The movement of one of the trolleys G will, through the rope K, move the other trolley an equal distance in the same direction. Each of the trolleys G is preferably placed midway between the end of the bridge and the main trolley B. Since each of these trolleys moves in the direction in which the main trolley moves but at half the speed, it is evident that, at all times, each of the trolleys G will occupy a position midway between the trolley B and the adjacent end of the bridge. The ropes D, E and F pass over and are supported by the sheaves g^3 , which sheaves will always support said ropes at points midway between the trolley and end of the bridge.

Having described my invention, I claim:

1. In hoisting and conveying apparatus, the combination of a movable trolley, and ropes which extend therefrom in opposite directions, two with sag-carrying trolleys which are located at opposite ends of the main trolley and are provided with devices which support said ropes, and means for positively moving the two sag-carrying trolleys simultaneously with the main trolley and in the same direction but at less speed.

2. In hoisting and conveying apparatus, the combination of a main trolley, two sag-carrying trolleys located at opposite ends of said main trolley, two ropes, each of which is associated with one of the sag-carrying trolleys and is connected with the main trolley and extends therefrom over a sheave on the associated sag-carrying trolley and thence back to a fixture to which it is secured, and means which positively connect the two sag-carrying trolleys and compel them to move simultaneously and quickly in the same direction.

3. In hoisting and conveying apparatus, the combination of a main trolley and ropes which extend in opposite directions from said

trolley, with two sag-carrying trolleys located at opposite ends of the main trolley, sheaves mounted upon each of the sag-carrying trolleys over which said ropes extend and by which they are supported, another sheave mounted in each of said sag-carrying trolleys, two ropes each of which is fixed at one end and extends therefrom over one of the last mentioned sheaves on the associated sag-carrying trolleys and thence back to the main trolley to which it is secured, and another rope which is secured at one end to one of the sag-carrying trolleys and extends therefrom away from the main trolley over a suitable sheave and thence back past the three trolleys and over another sheave and thence back to the other sag-carrying trolley to which it is made fast.

4. In hoisting and conveying apparatus, the combination of a movable trolley with ropes which extend therefrom in opposite directions, with sag-carrying trolleys which are located at opposite ends of the main trolley, and are provided with devices which support said ropes and means positively connecting the sag-carrying trolleys with the main trolley, adapted positively to regulate the speed carrying trolleys to the same direction and to a lower rate than the main trolley and to simultaneous movement therewith, said connections being independent friction.

5. In hoisting and conveying apparatus, the combination of a movable trolley and ropes which extend therefrom in opposite directions, with sag-carrying trolleys which are located at opposite ends of the main trolley, and are provided with devices which support said ropes, and cables positively connecting the sag-carrying trolleys with the main trolley and positively connecting the sag-carrying trolleys with each other so as to effect simultaneous movement of the sag-carrying trolleys and the main trolley and to cause the sag-carrying trolleys to move in the same direction with the main trolley but at less speed.

In testimony whereof, I hereunto affix my signature in the presence of two witnesses.

JOHN McMYLER.
